UNITED STATES PATENT OFFICE.

EVANDER M. USSERY, OF LITTLES MILLS, NORTH CAROLINA.

NON-REFILLABLE BOTTLE.

SPECIFICATION forming part of Letters Patent No. 767,455, dated August 16, 1904.

Application filed November 30, 1903. Serial No. 183,262. (No model.)

To all whom it may concern:

Be it known that I, EVANDER M. USSERY, a citizen of the United States, residing at Littles Mills, in the county of Richmond and State 5 of North Carolina, have invented certain new and useful Improvements in Non-Refillable Bottles, of which the following is a specification.

This invention relates to that class of devices commonly known as "non-refillable bottles," and provides a novel construction of guard means securing the operating-valve governing the outflow of the liquid in the neck of the bottle. The guard is of sectional 15 construction and is compressible, being made of a yielding or resilient material, so as to engage with the neck of the bottle and afford an interlocking connection between the neck and the guard.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying 30 drawings, in which—

Figure 1 is a vertical sectional view through the upper portion of a bottle having the invention applied thereto. Fig. 2 is a view similar to Fig. 1, showing the position of the guard and valve upon immersion of the bottle to cause outflow of the liquid therefrom. Fig. 3 is a combined view of the yielding section of the guard and the valve operatively connected therewith. Fig. 4 is a perspective 40 view of a rigid section of the guard.

Corresponding and like parts are referred to in the following description and indicated in all the views of the drawings by the same reference characters.

The bottle 1, as regards the construction of the body thereof, is of any ordinary type, a neck 2, however, being somewhat modified to provide an annular enlargement 3, forming an offset or grooved engaging portion 4 upon 50 the inner periphery of the said neck. The en-

largement 3 is formed in the manufacture of the bottle and constitutes engaging means cooperating with the yielding section 5 of the guard. As hereinbefore mentioned, the guard is of peculiar form, being constructed in two 55 sections 5 and 6. The section 5 is formed of yielding compressible material—such as cork, rubber, or the like—and is provided with an annular enlargement 7, which engages the annularly-grooved portion 4 of the neck of 60 the bottle. The section 6 of the guard is of rigid material, such as metal, and is secured to the section 5 by means of fastenings 8, which are passed through the respective sections and headed at opposite ends to secure 65 the parts 5 and 6 together. A metallic disk 9 is disposed upon the under side of the yielding section 5, so that the headed portions of the fastenings 8 may be engaged therewith, and thus more firmly hold the sections together. An opening 10 in the rigid section 6 admits of the outflow of the contents of the receptacle 1, and a valve 11 is mounted intermediate the sections 5 and 6 of the guard and adapted for movement in such position. The 70 under side of the section 6 of the guard is recessed, as shown at 12, to form a space within which the valve 11 is movable. The valve 11 is provided with guide-legs 13, projected from the under side thereof, which legs are 75 received by the opening 14, provided in the yielding section 5 of the guard, the valve being adapted to close down upon the upper side of the section 5 adjacent the opening 14 therein, to thereby normally close the said opening 80 and prevent introduction of the liquid or the like within the bottle after the original contents thereof have been removed. To space the valve 11 from the under side of the rigid section 6 of the guard when the bottle is inverted and admit of passage of the contents from the receptacle, lugs 15 extend from the upper side of the valve and serve in the capacity before stated.

A closure, such as a cork 16, is disposed above 95 the guard in the usual manner, and the receptacle may be sealed in any suitable way. As the bottle is in an upright position the valve 11 is normally closed and upon tilting of the bottle said valve readily opens, moving to- 100

- ward the opening 10 in the rigid section of the guard, and the contents of the receptacle pass around the valve and out of the neck in the usual manner. In placing the guard in 5 position in the neck of the bottle after the contents thereof have been placed therein the said guard is forced into the neck 2 and as soon as the enlarged portion 7 of the yielding section 5 arrives adjacent the annular 10 enlargement 3 the enlargement of the guard springs outwardly, being of course flexible, and engaging the neck is effectually locked in position, preventing removal of the guard without mutilation thereof.
- 15 A guard-plate 20 is secured to the upper side of the metal section of the guard and prevents tampering with the valve by the introduction of a tool into the neck of the bottle for fraudulent purposes.
- 20 Having thus described the invention, what is claimed as new is—
In a bottle or like necked receptacle, the combination with a neck provided with an an-

nular enlargement forming an annular groove upon the inner periphery thereof, an antire-filling-closure comprising an upper rigid section and a lower flexible or resilient section, the upper rigid section being provided upon its lower side with a recess, the sections of the closure being provided with outlet-openings therethrough, a valve arranged intermediate the sections aforesaid and movable in the recessed portion of the rigid section, said valve being provided with lugs projected from the upper side thereof to engage the rigid section, 30 guide-legs depending from the valve and movable within the opening of the flexible section, and a guard-plate arranged upon the sectional closure aforesaid.

In testimony whereof I affix my signature in 40 presence of two witnesses.

EVANDER M. USSERY. [I. S.]
